UNITED STATES PATENT OFFICE.

TENNEY L. DAVIS, OF SOMERVILLE, MASSACHUSETTS.

MERCURY NITRATE AS A REAGENT FOR THE PREPARATION OF NITROPHENOLS.

1,417,368.

Specification of Letters Patent. Patented May 23, 1922.

No Drawing.

Application filed April 16, 1921. Serial No. 462,029.

(FILED UNDER THE ACT OF MARCH 3, 1883, 22 STAT. L., 625.)

To all whom it may concern:

Be it known that I, TENNEY L. DAVIS, a citizen of the United States, and a resident of Somerville, county of Middlesex, and 5 State of Massachusetts, have invented an Improvement in Mercury Nitrate as a Reagent for the Preparation of Nitrophenols, of which the following is a specification.

The invention described herein may be 10 used by the Government, or any of its officers or employees in prosecution of work for the Government, or by any other person in the United States, without payment to me of any royalty thereon.

15 The subject of this invention is mercury nitrate as a reagent for the preparation of nitrophenols.

The main objects of the invention are a more absolute control of the process for the 20 production of nitrophenols and an increase in the yield of nitrophenols.

It is well known to chemists that nitric acid, alone or in the presence of sulphuric acid, acting on aromatic compounds yields 25 nitro derivatives. Thus, benzene, treated with nitric acid alone or with a nitric-sulphuric acid mixture yields nitro-benzene for the first product. It is also well known that nitric acid acting on aromatic substances in 30 the presence of mercury nitrate yields, in addition to the usual nitro derivative, a certain amount of the nitro-hydroxyl or nitrophenolic compounds. Thus, benzene treated with nitric acid in the presence of mercury 35 nitrate yields nitro-benzene and dinitrophenol. This second substance is converted by further treatment with nitric acid into picric acid or trinitrophenol; and the process of treating benzene with nitric acid in 40 the presence of mercury nitrate has been used for the technical preparation of picric acid.

In the processes used and described it has 50 been customary to use only a relatively small amount of mercury nitrate, for the reason that it has been supposed that the mercury salt acts catalytically and by presence, in some way facilitating the oxidation 55 by the nitric acid of the hydrogen atom of

the aromatic nucleus to an hydroxyl group. Since it has been supposed that the mercury salt acts catalytically, a small quantity of it has been supposed to be as efficient as a large quantity in leading to the formation of picric acid direct from benzene. 60

I have discovered that the mercury salt in such reactions does not function as a catalyst but as a real re-agent which enters into the chemical reaction. I have 65 found that the larger the amount of mercury salt which is used the greater is the yield of nitrophenol. By treating nitrobenzene, 1.3 dinitrobenzene, 1.3.5 trinitrobenzene, and 2.4.6 trinitrotoluene for several hours with 70 hot strong nitric acid in the presence of a molecular equivalent of mercury nitrate, I have adequately demonstrated that the presence of mercury salt does not facilitate the oxidation by means of nitric acid of the 75 hydrogen atom of the aromatic nucleus. In the case of nitrobenzene some nitration occurs, and, along with the nitrobenzene which was recovered there was obtained a considerable quantity of 1.3 dinitrobenzene. 80 In the case of the other three substances, the original material was recovered unchanged in practically theoretical amount. Trinitrobenzene and trinitrotoluene are readily oxidized by a gentle and oxidizing 85 agent as aqueous potassium ferricyanide, yielding respectively picric acid and trinitroresole, yet in my experiments they were unattached by prolonged treatment with nitric acid at a boiling temperature in the 90 presence of mercury nitrate. Trinitrotoluene is oxidized by hot nitric-sulphuric acid mixture, or more readily by chromic acid in sulphuric acid solution, to yield trinitrobenzoic acid. As none of this substance 95 was produced in my experiments, it is apparent that mercury nitrate does not act catalytically and by presence to facilitate the oxidizing action of nitric acid whether this oxidizing agent is conceived as acting 100 on the hydrogen of the aromatic nucleus or on the hydrogen of the side-chain.

I have discovered that nitric acid and mercury nitrate acting on benzene in the cold produce a complex compound which I 105 have isolated in the form of a black solid. This solid is soluble in nitric acid. Treated with hot nitric acid it reacts with it to form oxide of nitrogen, mercury nitrate, and 2.4 dinitrophenol or picric acid accord- 110

ing to the conditions of reaction. The formation of this complex compound requires a molecular proportion of mercury, and the compound when treated vigorously with 5 nitric acid yields a molecular proportion of dinitrophenol or picric acid. The mercury nitrate acts as a real reagent in the process. The knowledge that it does so makes it possible to carry out the first step of the re- 10 action under conditions which lead exclusively to the formation of the complex compound and so avoid the formation of simple nitro derivatives, like nitrobenzene; and to carry out the second step of the process un- 15 der conditions which decompose the complex compound into a nitrophenol while they do not at the same time produce its destructive oxidation by the nitric acid.

By this process I have prepared 2,4 dini- 20 trophenol and picric acid from benzene, trinitro-m-cresole from toluene, and trini- tro-*m*-chlorophenol from chlorbenzene. I

find that sulphuric acid interferes with the process, perhaps because it leads to the formation of a complex compound with mercury sulphate which decomposes in contact with the nitric acid to form substances different from the desired nitrophenols. 25

Having described my invention what I claim as new and desire to secure by Letters Patent, is:

1. The process of producing nitrophenols, comprising treating an aromatic compound with nitric acid and mercury nitrate to produce a complex compound and then decom- 35 posing the complex compound with nitric acid into nitrophenol.

2. The process of producing nitrophenols, comprising treating an aromatic compound, using a mercury salt as a re-agent, to produce a complex compound and then decom- 40 posing the complex compound with nitric acid into nitrophenol.

TENNEY L. DAVIS.
